UNITED STATES PATENT OFFICE.

RODOLPHE NAVET, OF TUBIZE, BELGIUM.

PRESS FOR THE MANUFACTURE OF BRICKS, TILES, AND SIMILAR ARTICLES.

Application filed February 14, 1924. Serial No. 692,793.

To all whom it may concern:

Be it known that I, RODOLPHE NAVET, a subject of the King of the Belgians, and resident of Tubize, Belgium, have invented certain new and useful Improvements in Presses for the Manufacture of Bricks, Tiles, and Similar Articles, of which the following is a specification.

In presses for the manufacture of bricks, tiles, plates and the like, the pressure on the piston is generally obtained by means of a beam which, when raised at one end pushes the piston upwardly swinging around its other fixed end. Said beam or lever therefore has arms of practically constant length.

However the material to be pressed varying frequently: clay, slag, ashes, lime, cement and the like, as well as the thickness and nature of the articles to be manufactured, it will be understood that the pressure to be produced on the mould by the piston is also to be changed according to each particular case in order to obtain perfect finished products. Again when treating the same material to produce similar articles, the pressure produced depends on the operator so that, all other conditions remaining the same, the result obtained will vary according to the power and size of the operator.

However it is an important feature to obtain the same finished article without regard to the operators, and with the same operator to increase and decrease the pressure according to the material and nature of the articles to be manufactured. The length of the upward stroke of the piston must also be adjustable.

On the other hand if the movement of the operator's arm during the pressing operation is considered, it will be seen that the operator first produces a pull on the operating lever which pull will progressively decrease to become nil at the moment, the hand coming to the height of the shoulder, the pull will be converted into pressure, the lever being more and more inclined. Thus it will be seen that in the curve representing the stress of the operator—if he does not change his position—there will be a point of inflection adjacent which the stress will be very much reduced. This constitutes a serious objection, adherent to all machines in which the operator has to produce a pull and then a pressure on the lever. It will be under-

stood that an upward stroke of the piston corresponding to each angular movement of the lever and the resistance opposed to said stroke remaining the same or rather increasing, the operator cannot easily pass the "dead centre" and he is frequently obliged to stand back or use both hands. In any case there will be an increase of fatigue for the operator.

The object of my present invention is:

(1) To allow the variation of the power and resistance arms of the beam, the point of application of the resistance remaining substantially fixed.

(2) To stop or nearly stop the upward stroke of the piston in the neighborhood of the point of inflection mentioned, so that the light stress produced at this moment by the operator will only serve to move the lever through the dead centre. This result may be obtained in different ways, and in the accompanying drawings I have illustrated one preferred embodiment by way of example.

Fig. 1 shows the supporting frame for the pivot pin of the pressure beam.

Fig. 2 shows the support for the pivot-pin of the operating lever, enabling the length of the power arm of the pressure beam to be varied.

Fig. 3 shows the system of transmission from the operating lever to the pressure beam.

Referring to Figs. 1 and 2, the pivot pin 1 of the beam 2 is inserted into one of the recesses 3 in a part 4 secured to the frame of the machine. The end of the beam is provided with corresponding recesses 5, whereby the pivotal point may be changed and the resistance arm increased or decreased without changing the power arm. The length of the latter may also be changed by making the pivot-pin 6 of the operating lever 7 adjustable along a fixed part on the frame, said operating lever 7 transmitting the stress of the operator to the beam (through a suitable transmission). Said adjustment may be effected by means of a number of adjusting holes 8 provided in the fixed part 9 and serving to receive bolts attaching the bearings of the pivot-pin 6.

Referring to Fig. 3, the rear part of the beam 2 is submitted to the stress of the operating lever 7 through the medium of a small

lever 10 the free end of which is equipped with a roller 11 and which is mounted on the pivot-pin of the operating lever 7. The lever 10 and its roller 11 are not located in the vertical plane of the beam 2, but somewhat outside thereof so that the transmission of power will not be effected directly from the roller 11 to the beam 2, but through the agency of a part 12 secured to the beam 10 and on the lower rim of which acts said roller 11. Said rim is made of a special profile or cross section: an upwardly inclined portion 13 corresponding to the traction period on the operating lever. Then a depression 14 whereby the beam (and therefore the piston) is allowed to be not raised during the passage through the dead centre, and at least an inclined portion 15 corresponding to the pressure period on the operating lever. It will be understood that owing to the part 12 secured to the beam, the operator may easily pass beyond his shoulder joint with constant effort. Of course said part 12 will be adjustable on the beam 2. 25 As an example and for a normal operator or workman the duration of the contact of the roller 11 with each of the three portions of the part 12 should correspond—the operating lever swinging through an angle of 30 72° —to a revolution of said lever of 28° for the portion 13, 18° for the portion 14 and 26° for the portion 15.

Having now fully described my said invention, what I claim and desire to secure by Letters Patent, is:

35

1. In a press, a frame support, a pressure beam, said pressure beam and frame support being formed with a plurality of pivot openings, said pivot openings being formed partly in each of said members, and a pivot pin 40 adapted to cooperate with either of said openings without changing the relation of the frame support and pressure beam, to thereby vary the leverage of the beam.

45

2. In a press, a pressure beam, an operating lever, and means interposed between said lever and beam to substantially nullify the effect of the lever on the beam during a portion of the lever movement intermediate the initial and final movements of such lever. 50

55

3. In a press, a pressure beam, an operating lever, and a section secured to said beam to be engaged by said lever for the operation of the beam, the lever engaging portion of said section being interrupted for a portion of its length to permit an operative movement of the lever without materially affecting movement of the beam during co-operation of the lever with said interrupted portion.

60

In testimony whereof I have hereunto set my hand.

RODOLPHE NAVET.
